DEVICE FOR FOLDING BOX BLANKS

Ernst Landolt, Neuchatel, Switzerland

Application June 28, 1945, Serial No. 602,046
In Switzerland September 20, 1944

4 Claims. (Cl. 93—49.)

1

Collapsible boxes of card board suitable for packing fruit cakes, cakes coated with cream and so forth; that is to say, for articles of which the satisfactory appearance is liable to be damaged by contact with or by pressure from unsuitable packing are now in common use. Packings for articles of this character must not be too expensive by reason of the low cost of the article; however, they must constitute a fairly firm or rigid packing so that the article is not damaged when being carried from the shop to the house or the like.

The main object of the invention consists in the provision of a device to aid the filling-in of the goods and the closing of boxes. The invention will be described hereinafter with reference to a folding box of light cardboard which is erected from a blank having a central rectangular area and uncreased flaps, providing side members and top closure members collectively forming a dome at the top of the erected box. The box has its corners closed and its sides made to remain substantially planar when the box is erected by means of end pieces hingedly secured to the ends of the said sides and each weakened, e. g., creased, on a line extending from the corner of the central rectangular area.

According to the invention the new device consists in a plate of metal, artificial resin, or the like adapted to receive the blank while the same is partly folded so as to receive the goods to be packed. The plate gives the open box a firm hold while it is being filled and can be easily held by one hand only.

In the accompanying drawings a preferred mode of construction of the new device is shown in connection with a blank of a folding box.

In the drawings:

Fig. 1 is a plan view of a blank of thin card board to be folded to form a box.

Fig. 2 is a plan view of a plate or tablet to receive and to hold the partly formed box while it is being filled.

Fig. 3 is a cross-section on the line 3—3 of Fig. 2.

Fig. 4 shows the box fully folded in a side view.

The blank to be folded by the new device consists of a sheet 1 of paste board, stiff paper or the like and is provided with a rectangular, for example square, central area 2. Along the sides of this area four flaps or panels 5 and 6 are formed by scoring lines 3 and 4 respectively in the sheet. Each flap 6 is provided at its free end with a tongue 7 and a slit 8 for latching engagement after the blank has been folded. Between adja-

cent flaps 5 and 6 is provided an end-piece 9. The end-pieces are provided with extensions of the scoring lines 13 and 14 and each with an additional diagonal scoring line 12. Instead of these scoring lines there may be provided similarly positioned weakening lines, for example, perforations, for facilitating the bending of the sheet without resistance. The scoring line 12 is not located exactly in the middle between the scoring lines 13 and 14, the angle between lines 12 and 13 in each case being slightly less than the angle between lines 12 and 14 so that, on folding, the lines 14 offer a greater resistance to bending than do the lines 12 and 13. Thus, when the carton is erected, the panels 5 tend to come together first and the panels 6 then to overlap them. Moreover the end-pieces 9 tend thereby to lie flat against the wall panels 6 and not to project into the interior of the carton; if desired, the inner parts of the lines 12 and 13 may be further weakened by perforations or scoring lines cut right through the material of the blank.

The assembled flaps form a wide arch extending over the central area. The side walls of the closed box are at least substantially vertical. The two flaps 5 are slightly shorter than the flaps 6. When the box is closed the flaps bear firmly against one another and strengthen the box considerably.

To facilitate the filling-in of small pieces of confectionery or the like the device shown in Figs. 2 and 3 is used. The device consists of a plate 20 of strong artificial resin, of stiff sheet, metal or the like. This plate comprises a substantially flat base 19 having stiffening ribs 16 and, upstanding from the contour 18 at said base, upwardly and outwardly flared side walls or edges 21. The edges 21 are upturned, leaving between themselves a space corresponding to the central area 2 of the blank and the scoring lines 3 and 4 thereof. The plate 20 is provided at its corners with vertical guiding lugs 22 to guide the blank 1 during insertion in the plate 20, and at each corner with a tooth 23. Each tooth 23 is provided with a sharp curved edge 24 coinciding with the scored lines 12 of the blank 1. By inserting the blank between the edges 21, the flaps 5 and 6 are turned upwardly about the scored lines 3 and 4. The edge portions 9 of the blank are folded as the edge 24 of each tooth 23 meets the scored line 12. The blank assumes now the position shown in broken lines in Fig. 3. The goods to be packed may be easily inserted. To facilitate the holding of the plate 20 by but one hand together with the con-

tainer to be filled the plate 20 is provided with two incuts 25.

The dimensions of the plate 20 and of the blank are such that the sides of the box fit tightly between the edges 21. When filled the box is closed by uniting the flaps as shown in Fig. 4.

For each size of package a plate of appropriate size is being used.

What I wish to secure by U. S. A. Letters Patent is:

1. A device for folding a blank to erect an open box and subsequently supporting the same, comprising a substantially rectangular base including edges, side walls forming a frame around said base, each side wall connected to an edge of said base and flaring upwardly and outwardly therefrom and adapted to fold a blank along crease lines thereof corresponding substantially to said edges, when said blank is inserted manually in said device, and a plurality of spaced teeth, each carrying an edge curved inwardly and upwardly with relation to said base, said teeth disposed on said frame near intersecting lines formed by said side walls and each adapted to crease a crease line of a lug angularly disposed with relation to said first mentioned rectangular crease lines, for aiding in the folding of a box, said base having at least one slot extending from the interior of said base through the edge and through the side-wall adjacent thereto, for facilitating manual removal of the folded box from emplacement in said device.

2. A device for folding a blank to erect an open box and subsequently supporting the same, comprising, a substantially rectangular base including edges, side walls forming a frame around said base, each two side-walls oppositely disposed along opposite edges of said base and having convex inner surfaces facing each other having their lines of closest proximity at said edges flaring outwardly and upwardly from said edges, thereby continuously increasing the space between opposite lines of said side walls with increasing distance from said edges, said frame having at least one slot extending vertically throughout one of said side walls to the adjacent edge of the base, for facilitating manual removal of the folded box from emplacement in said device.

3. In a device for folding a blank along crease lines thereof to erect an open box, said blank having a base portion surrounded by crease lines, flaps connected to said base portion at said crease lines foldable about said lines to form the walls of a box and end-pieces connected at the corners

of said base to two adjacent flaps, each end-piece having a crease line at the line of connection with each flap and having an angularly off-set crease line intermediate said two crease lines, said device comprising a base corresponding in outline to said base portion of said blank, side walls forming a frame around said base and flaring outwardly and upwardly therefrom for engaging said flaps to be erected relative to said base portion when the latter is inserted into said device, and a plurality of upwardly curved edges connected with relation to said base for engaging said angularly off-set crease lines of said end-pieces for folding the same, whereby the folding of said flaps will be facilitated.

4. In a device for folding a blank along crease lines thereof to erect an open box, said blank having a base portion surrounded by crease lines, flaps connected to said base portion at said crease lines foldable about said lines to form the walls of a box and end-pieces connected at the corners of said base to two adjacent flaps, each end-piece having a crease line at the line of connection with each flap and having an angularly off-set crease line intermediate said two crease lines, said device comprising a base corresponding in outline to said base portion of said blank, side walls forming a frame around said base and flaring outwardly and upwardly therefrom for engaging said flaps to be erected relative to said base portion when the latter is inserted into said device, and a plurality of upwardly curved edges connected with relation to said base for engaging said angularly off-set crease lines of said end-pieces for folding the same, whereby the folding of said flaps will be facilitated, said base having at least one slot extending from the interior of said base through the edge and through the side-wall adjacent thereto, for facilitating manual removal of the folded box from emplacement in said device.
